W. S. NICOLSON

SODA FOUNTAIN AND ICE CREAM CABINET

Filed Aug. 28, 1922

Inventor

WILLIAM S. NICOLSON,

Eccleston & Eccleston

Attorneys.

UNITED STATES PATENT OFFICE.

WILLIAM SAMUEL NICOLSON, OF SALISBURY, NORTH CAROLINA.

SODA FOUNTAIN AND ICE-CREAM CABINET.

Application filed August 26, 1922. Serial No. 584,785.

To all whom it may concern:

Be it known that I, WILLIAM S. NICOLSON, a citizen of the United States, and a resident of Salisbury, in the county of

5 Rowan and State of North Carolina, have invented certain new and useful Improvements in Soda Fountains and Ice-Cream Cabinets, of which the following is a full, clear, and exact description.

10 My invention relates to improvements in soda fountains and ice cream cabinets, and one of the objects of my invention is to provide an apparatus of this character which is neat and attractive in appearance, 15 relatively cheap in manufacture, and which will produce an entirely sanitary beverage.

Another object of my invention resides in arranging the interior of a container, such as a barrel, in such manner that there will be space allotted for syrups, space for ice cream, a cooling coil, space for ice to be packed around the syrups, ice cream, and cooling coil, and an air space at the bottom of the barrel or other container for the reception of foods, etc.

A further object of my invention resides in the provision of a soda fountain of this character which is equally well adapted to either stationary or portable use.

30 Other and further objects and advantages of my invention will be apparent from the following detailed description, when taken in connection with the accompanying drawings; in which,

35 The figure is a perspective view of the interior of the fountain and cabinet, parts being broken away to more clearly show the construction.

Referring to the drawings more in detail 40 numeral 1 indicates generally the cabinet, which in the particular form of the invention illustrated herein consists of a barrel, which will of course be highly varnished and otherwise ornamented to present an attractive appearance. I have shown the barrel or cabinet as provided with legs 2, but it will be understood that rollers may be substituted for the legs for the purpose of rendering the device portable, or the entire 45 apparatus may be mounted in a vender's cart.

A cylindrical partition 3, which is preferably metallic, is mounted in the upper portion of the cabinet and extends downwardly from the top thereof to a point at some little distance from the bottom. The

lower end of the cylindrical partition is provided with a bottom 4, which is preferably of wood; and on the interior of the cylindrical partition is a lining 5 of insulating material, such as asbestos. The cylindrical partition, together with its bottom, divides the cabinet or barrel into a refrigerating space or ice box 6, and air space 7.

60 The interior of the refrigerating space is adapted to be filled with ice, and mounted on the floor thereof are standards 8 carrying a conventional copper cooling coil 9, which is connected at the top by a suitable union to an ordinary soda dispensing faucet 10. At its lower end the coil is connected with a pipe 11 leading through the bottom of the barrel or cabinet to a carbonator or charge fountain container, whereby the 70 fountain is adapted to use in either large or small establishments. It is thus seen that the carbonated or other water will be maintained ice-cold, so that it will not be necessary to add ice to the beverage.

80 Mounted in the upper portion of the refrigerating space are a plurality of syrup jars 12, four of the jars being employed in the construction illustrated, and mounted on the top of the barrel are conventional 85 syrup dispensing pumps 13 communicating with the syrup jars.

A perforated container 14, preferably of zinc or copper, is also mounted in the upper portion of the refrigerating space; a door 90 15 in the top of the barrel affording means of communication with the interior of the container. This container will be packed with ice, and will receive the ice cream can (not shown).

A draw off tap 16 communicates with the interior of the refrigerating space, adjacent the bottom thereof.

The lower portion of the barrel is provided with a door 17 communicating with the air space; the air space being utilized for the storage of food, etc. A hole 18 in the bottom of the air space assists in the drainage and ventilation of this space; the hole being closed, when desired, by means of a plug (not shown).

100 My novel construction of fountain and ice cream cabinet, and the many advantages thereof, will be apparent from the foregoing 105 detailed description.

110 The fountain presents an extremely neat and attractive appearance, and by the com-

pact arrangement of the various elements the entire interior of the barrel is utilized in the most advantageous manner.

The syrups, the carbonated or other water, 5 and the ice cream, are all packed in ice, and all of the ingredients of the beverages are thus maintained ice-cold, and there is no necessity for adding ice to the beverages. Another of the obvious advantages of my 10 construction is that I have provided an apparatus of this character which is absolutely sanitary.

Further, by the construction described, an 15 air space entirely separate from the refrigerating space is provided; and the air space presents a most desirable and convenient place for the storage of food, etc.

A further advantage of my invention is 20 that the fountain is readily portable. It may be mounted on a vender's cart, or it may be mounted on rollers or wheels, if desired.

In accordance with the patent statutes I 25 have described what I now believe to be the best embodiment of the invention, but I do not wish to be understood thereby as limiting myself or the scope of my invention, as many changes and modifications may be made without departing from the spirit of the invention, and all such I aim to include 30 in the scope of the appended claims.

What I claim as new and desire to secure by Letters Patent is:

1. An apparatus of the character described 35 including a barrel, a cylindrical metallic partition extending from the top of the barrel to the lower portion thereof, a lining of insulating material arranged on the interior of the partition, said cylindrical partition being closed at its lower end, whereby the 40 barrel is divided into a refrigerating cham-

ber and an air chamber, beverage dispensing means arranged in the refrigerating chamber, and a door provided in the barrel and communicating with the air chamber.

2. An apparatus of the character described 45 including a barrel, a cylindrical metallic partition extending from the top of the barrel to the lower portion thereof, a lining of insulating material arranged on the interior of the partition, said cylindrical partition being closed at its lower end, whereby the barrel is divided into a refrigerating chamber and an air chamber, syrup jars mounted in the upper portion of the refrigerating chamber, and conventional 50 syrup pumps communicating with the syrup jars, and a door provided in the barrel and communicating with the air chamber.

3. An apparatus of the character described 55 including a barrel, a cylindrical metallic partition extending from the top of the barrel to the lower portion thereof, a lining of insulating material arranged on the interior of the partition, said cylindrical partition being closed at its lower end, whereby the 60 barrel is divided into a refrigerating chamber and an air chamber, a door provided in the barrel and communicating with the air chamber, a cooling coil mounted in the refrigerating chamber, said coil communicating 65 at one end with a supply of water and at the other end with a dispensing faucet, a plurality of syrup jars mounted in the upper portion of the refrigerating chamber, a plurality of syrup pumps mounted on the 70 top of the barrel and communicating with the syrup jars, and a container mounted in the upper portion of the refrigerating chamber and adapted for the storage of ice cream.

WILLIAM SAMUEL NICOLSON.
